CLAIM

The ornamental design for a telescope, as shown and described.

DESCRIPTION

FIG. 1 is a perspective view of a telescope according to my novel design;

FIG. 2 is a top view of the telescope according to my novel design;

FIG. 3 is a bottom view of the telescope according to my novel design;

FIG. 4 is a front view of the telescope according to my novel design;

FIG. 5 is a rear view of the telescope according to my novel design;

FIG. 6 is a side view of the telescope according to my novel design; and,

FIG. 7 is a side view of the telescope according to my novel design.

The broken line showing of the central circular member in FIGS. 1 and 2 is for illustrative purposes only and forms no part of the claimed design.
